ATTORNEY

UNITED STATES PATENT OFFICE.

TIMOTHY L. LINGG, OF PHILADELPHIA, PENNSYLVANIA.

COLLAPSIBLE UMBRELLA.

Application filed September 12, 1927. Serial No. 219,123.

It is conclusive that umbrellas constitute luggage that seems to be in the way, especially when it is necessary to carry dress suit cases, brief cases and the like, therefore the present 5 invention relates to an improved collapsible umbrella of such construction that it is possible to collapse or fold the same in small compass and carry it in the brief or dress suit case or in a similar carrier.

10 It is the purpose of the present invention to provide a very simple construction of a collapsible or foldable umbrella, wherein the ribs are telescopically constructed, and the stick composed of a plurality of telescopic 15 sections, with means for holding the sections of the stick in different positions, said means to be actuated by a device or button adjacent the handle of the stick, so that such holding means may be easily operated to release the 20 sections, to allow the stays and ribs to collapse and the umbrella made into a small compass whereby it may be easily and conveniently placed in a brief or dress suit case, thereby in 25 this manner avoiding carrying an article or excess luggage separate from the brief or dress suit case.

It is to be understood that the particulars herein given are in no way limitative, and that 30 while still keeping within the scope of the invention, any desired modification of details and proportions may be made in the construction of the appliance according to circumstances.

The invention comprises further features 35 and combination of parts to be hereinafter set forth, shown in the drawings and claimed.

In the drawings:

Figure 1—is a view showing the umbrella collapsed or folded.

40 Figure 2—is a sectional view through the same with the parts in the same position as in Figure 1.

Figure 3—is a vertical sectional view through the umbrella open.

45 Figure 4—is an enlarged detailed sectional view through the two sections of the stick, showing the means for holding the handle section in different positions, and the connections with the manually actuated button or lever for operating the holding means, whereby one section may be adjusted relative to the other.

50 Figure 5—is an enlarged detailed view of the runner which carries the stays, showing a device for holding the runner in different positions.

Figure 6—is an enlarged detailed view of one of the ribs showing its telescopic connection between its sections.

55 Figure 7—is an enlarged detailed vertical sectional view through a portion of a stick showing parts of the two sections 2 and 3 and illustrating the means for holding the section 2 extended.

Figure 8—is a sectional view on line 8—8 of Figure 7.

Figure 9—is a detailed vertical sectional view more clearly illustrating the dogs 31.

Referring to the drawings, 1 identifies the umbrella stick, which consists of two sections 70 2 and 3. These sections are telescopically united and are tubular, and angular or square in cross section to retain the sections against rotation relative to each other yet permitting them to move freely longitudinally. The section 3 carries the usual umbrella head 4, to which the ribs 5 are connected by the usual wire 6, which is twisted in an approved manner thus preventing detachment from the ribs.

75 Each rib consists of two sections 9 and 10, and are U-shaped in cross section, so that the section 10 will telescopically enter the section 9, which has two guides or arches, 11 and 12, through or under which the section 10 is moved, one of which limits the movement of 85 the section 10 of the rib.

80 The stays 14^a are connected pivotally as at 13 to the inner ends of the sections 10 of the ribs. The stays are in turn pivotally connected by means of a wire 14 to a runner 15, which is slideable on the sections of the stick. The runner 15 is provided with a spring 90 pressed locking dog 17 pivoted at 18, and its nose passes through an opening in the runner and is designed to engage either the opening 19 near the handle 20 of the section 2 to hold the umbrella in a closed or folded position, or may engage with the opening 21 of the section 3 of the stick to hold the umbrella open.

95 The section 3 of the stick is provided with opposite longitudinal slots 22, which are engaged by the spring pressed dogs 23 carried by the section 2 of the stick, the spring means thereof being identified at 24 and held in 100 place as by the rods or pins 25. The dogs engage with the slots to limit the section 2 of the stick in its extensible position when the umbrella is open. However the dogs 23 are so arranged as not to prevent the telescopic closing movement of the section 2 of 110 the stick. However when the section 2 of

the stick is arranged in an extended position the dogs 23 will engage the lower ends of the slots and limit the section 2 in position. The section 2 is tubular, and disposed for operative movement therein is a rod 26, which is pivotally connected to a lever 27 pivotally mounted in the handle of the umbrella as at 28. This handle has a button or device 29. The other end portion of the rod 26 has an enlargement 30 to which the dogs 31 are pivotally connected. These dogs are so arranged that when the rod 26 is moved in one direction said dogs will retract from engagement with the openings of the section 3 of the stick. It is to be noted that the dogs 31 also move through openings 33 constructed in the section 2 of the stick. However, these dogs never entirely disengage from the openings 33 of the section 2 of the stick, due to the fact that the rod 26 is limited in its movement in one direction by means of the shoulder 34, while the head 35 will engage a shoulder 36 on the interior of the section 2 of the stick to limit the rod in its movement in the opposite direction.

When the section 2 of the stick is moved longitudinally through the section 3 to collapse the stick, the dogs 31 will engage opposite openings 37 in the section 3 to hold the section 2 in its collapsed position.

When the stick is collapsed and the ribs collapsed and the umbrella folded, the covering of the umbrella may be folded and arranged neatly as in Figure 1 in which case the umbrella may be placed in a dress suit or brief case and be entirely out of the way, enabling the person to carry the umbrella without any inconvenience whatever.

The dogs 23 engaging with the slots when the handled section is extended, will always limit the handled section in a position so as to register the openings of the section 3 with the openings of the section 2, so that the dogs 31 will always enter the openings of the section 3.

The dogs 31 are mounted pivotally in a slot 31^a of the enlargement 30, in the opposite ends of which two sections 26^a and 26^b of the rod 26 are threaded.

A tensioned spring 20^a is attached to the rod 26 where its end terminates in the handle 20, and the other end of the spring is attached at 20^b to the end of the hollow of the handle. This spring so tensions the rod 26 as to hold the head in contact with the shoulder 36, to retain the dogs 31 protruded into the openings 37 of the section 3 of the stick.

Where the end of the section 2 must pass the nose of the locking dog 17, one edge of said end may be beveled to allow the section 2 to telescope into section 3.

The invention having been set forth, what is claimed is:

1. In a collapsible umbrella, the combination with an umbrella stick composed of tele-

scopically united sections, the sections being hollow, one section of the stick having opposite openings, the other section of the stick having pivotally connected and operatively associated dogs, a rod connected to said dogs, and means for limiting said rod for extending and retracting the dogs through the wall of the section of stick, and a lever operatively connected to the rod for actuating the same.

2. In a collapsible umbrella, a stick comprising two sections, one having a handle, said sections of the stick being telescopically united and hollow, the other section of the stick having opposite openings, the handle section having opposite openings to register with the first openings, pivoted dogs at all times engaging through the second openings, a rod in the handle section and operatively associated with the dogs for extending and retracting the dogs into and out of engagement, with the first openings, to hold the handled section in different positions with relation to the section having the first openings, and means for manually operating the rod.

3. In a collapsible umbrella, a stick comprising two sections, one having a handle, said sections of the stick being telescopically united and hollow, the other section of the stick having opposite openings, the handle section having opposite openings to register with the first openings, pivoted dogs at all times engaging through the second openings, a rod in the handle section and operatively associated with the dogs for extending and retracting the dogs into and out of engagement with the first openings, to hold the handled section in different positions with relation to the section having the first openings, and means for manually operating the rod, means for retaining the dogs in engagement with the second openings at all times.

4. In a collapsible umbrella, a stick comprising two sections, one having a handle, said sections of the stick being telescopically united and hollow, the other section of the stick having opposite openings, the handle section having opposite openings to register with the first openings, pivoted dogs at all times engaging through the second openings, a rod in the handle section and operatively associated with the dogs for extending and retracting the dogs into and out of engagement with the first openings, to hold the handled section in different positions with relation to the section having the first openings, and means for manually operating the rod, means for retaining the dogs in engagement with the second openings at all times, and means for limiting the handled section in a position whereby the first and second openings will always register whereby the dogs may engage through the first openings when the rod is actuated.

5. In a collapsible umbrella, the combina-

tion with a stick comprising tubular sections telescopically united, one section having opposite openings, the other section having opposite openings, of a pair of pivotally united 5 dogs at all times engaging through the second openings, a rod operatively associated with the dogs for extending and retracting the dogs into an outer engagement with the first openings, a device operatively mounted 10 in and carried by the section having the sec-

ond openings and in turn operatively connected to the rod for actuating the latter, and means for limiting the rod in its movement, whereby the first and second openings may approximately register, whereby the dogs 15 may be extended into engagement with the first openings.

In testimony whereof he affixes his signature.

TIMOTHY L. LINGG.
